UNITED STATES PATENT OFFICE.

WILLIAM C. STEWART, OF SWAMPSCOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

METHOD OF MAKING SHOES.

1,342,469.

Specification of Letters Patent.

Patented June 8, 1920.

Application filed September 6, 1917. Serial No. 189,933.

To all whom it may concern:

Be it known that I, WILLIAM C. STEWART, a subject of the King of England, residing at Swampscott, in the county of Essex and 5 State of Massachusetts, have invented certain Improvements in Methods of Making Shoes, of which the following description, in connection with the accompanying drawings, is a specification, like reference characters 10 on the drawings indicating like parts in the several figures.

This invention relates to the manufacture of shoes and more particularly to improvements in methods of manufacturing shoes.

15 The primary object of the invention is to provide an improved method of manufacturing shoes the practice of which will effect an improvement in the quality and uniformity of the shoes produced and an 20 economy in the cost of producing the shoes.

In the manufacture of shoes the insole, or it may be a sole, to which the shoe upper is to be secured is positioned on the bottom of a last which is of the shape desired for 25 the finished shoe and over which the shoe upper is to be conformed in the making operations. When the various operations on the shoe have been completed, the last is withdrawn and the insole remains as the 30 form largely determining and maintaining the desired shape of the shoe during its wear. It is, therefore, important initially to position the insole accurately on the last and to secure it against displacement there-

35 on during succeeding operations so that after the last is withdrawn from the shoe it shall have the intended contour and style. It has heretofore been customary to place the insole on the bottom of the last and secure it in position with three to seven tacks 40 driven perpendicularly through it and into the last bottom. These tacks necessarily have to be pulled out before they are covered up by the outsole so that the last can be 45 removed from the shoe. Also in order to enable the insole securing tacks readily to be pulled they must be located far enough inwardly from the margin of the insole to remain uncovered by the lasted-in margin of 50 the shoe upper and consequently the tacks are not enabled to hold the margin or feather of the insole down to the bottom of the last. This condition is directly opposed to a proper lasting of the shoe because in order

to last the shoe tightly and apply proper 55 tension to the shoe upper the feather or margin of the insole must be held down securely on to the last. In making turn shoes in which the edge of the sole extends beyond the edge of the last and also in making light-weight welt shoes in which the feather of the insole is thin, this difficulty is particularly troublesome. In fact, the 60 conditions are so serious as to necessitate the construction of special equipment for pulling over and lasting machines to hold down the feathers of soles and insoles on the last bottoms while the shoe parts are being 65 worked over on the shoe bottoms. Moreover, special machines have had to be devised for pulling out the insole fastening tacks after the shoe upper has been secured to its insole, and it is difficult even with the use of these machines or with hand work to 70 insure that every tack is pulled and that 75 the head of the tack is not broken off with the shank of the tack remaining in the insole with the consequent liability of injury to the wearer. Some shoe manufacturers incur the expense of employing help to examine the inside of each shoe for tacks before the shoes are packed for sale.

With the above conditions in view, the present invention aims to provide a method of securing soles or insoles to lasts which 85 will eliminate among others the difficulties and disadvantages above noted and materially reduce the labor and machine cost 90 incident to the prior practice. As has already been indicated, the invention is applicable to the securing to a last not only of the insole of a double soled shoe but also of the sole of a single soled shoe and, therefore, the term "insole" is herein used in a 95 generic sense to cover both.

In one of its aspects, this invention consists in binding the margin or feather of an insole down into position on the bottom of the last. As herein illustrated, this is accomplished by employing a readily tearable or frangible quality of adhesive coated paper in strip form. Preferably a plurality of the binding strips are located along the margin of the insole and they may be connected to the insole and extended down onto 100 the side face of the last and caused to adhere so as to bind the feather of the sole firmly pressed against the last bottom.

After the upper has been applied to the last and the succeeding operations upon the shoe completed, the withdrawing of the last from the shoe acts to tear the portion of the binder 5 that adheres to the last from the portion that remains connected to the insole, which latter portion may stay in the shoe without disadvantage.

In another of its aspects, the invention 10 consists in weakening or disrupting the binding strip as an incident to the performance of succeeding operations on the shoe after the shoe upper has been secured to the insole so that the binder strip offers 15 little, if any, resistance during the last pulling operation. This weakening or destroying of the binder is particularly applicable to the manufacture of shoes of the type in which the insole or sole has a sewing rib 20 provided on its upper surface. In making shoes of these types, the sewing needle, during the attachment of the upper to a sole or insole, serves to perforate the binder where it bridges from the feather to the 25 sewing rib and more or less completely severs the portion on the insole from the portion on the last. Also, the operation of the lasting wipers in wiping the margin of the shoe upper into the angle against the 30 sewing rib may tear the binders, but this occurs after the purpose of the binder has been accomplished. In this case, however, merely the binders about the toe end and possibly the heel end of the shoe will be 35 destroyed.

The above and other objects and advantages of the invention will be apparent from the following description when considered in connection with the accompanying drawings and the invention will then be defined in the appended claims.

Figure 1 of the drawings is a perspective view illustrating an insole fastened to its last without the use of tacks and in accordance with the present invention;

Fig. 2 is a perspective illustrating how the binders are perforated by the welt sewing needle in the practice of the present invention in the manufacture of welt shoes. 50 By way of illustration the invention is herein shown as being practised in connection with the manufacture of a welt shoe in which case the insole 2 is provided with a sewing rib 4. In carrying out the process 55 of the invention the insole 2 is initially placed in position upon the bottom of a last 6 of desired shape over which a shoe upper 8 is to be conformed by usual pulling-over and lasting operations. The insole having been positioned accurately with the edge 60 flush with the edge of the last, is then firmly secured in its assembled position on the last with the margin or feather portion 10 of the insole securely held down on the last bottom 65 by means of a plurality of binders 12, shown

as narrow strips of easily tearable adhesive coated paper of a length to extend from the upper surface of the insole outwardly over the sewing rib 4 to the side faces of the last. Preferably the strips will be located at the 70 toe and at substantially the tip line, ball line and heel breast line on either side of the insole.

In applying the binding strips to the insole the adhesive coating on the under side 75 of the strips is treated to cause it to adhere and the inner end of the strips pressed down on to the surface of the insole within the sewing rib the strip being then drawn tight over the edge of the insole and last 80 and its outer end folded over against the side of the last. The binding strips may be applied in such manner as to bridge from the sewing rib over the feather to the side of the last, as indicated in Fig. 1, although if 85 desired they may be formed into the angle between the feather 10 and the upstanding rib on the insole. It will thus be seen that the insole is firmly secured against displacement on the last bottom 6 and the margin 90 of the insole held firmly down on the last bottom. The shoe upper 8 is then assembled on the last and the succeeding operations on the shoe *e. g.* pulling over, lasting, bottoming and finishing, performed in the usual 95 manner.

By binding the margin of the insole down on to the last bottom as described, the tendency of the upper to raise the margin of the insole from the bottom of the last during 100 the application of tension to the shoe upper by the pulling-over and lasting operations is effectively prevented.

In making shoes with the aid of a "bed" lasting machine the wipers are enabled to 105 wipe up the side faces of the last and then wipe the upper in over on to the insole and into position to be fastened by the usual toe binding wire against the sewing rib 4 without liability of the wipers displacing the 110 margin of the sole and consequently enabling a better defined and more uniform margin for the shoe to be obtained. The operation of the wipers at the toe of the shoe serves, if the binding strip bridges the 115 angle between the feather and the sewing rib, to break down or destroy the binding as the upper is wiped into final position on the shoe bottom, so that when the last is withdrawn the binding strip at the toe of the 120 insole does not resist the last pulling operation. When the welt 14 and upper are secured to the insole by the inseam stitches 16 the needle of the sewing machine serves to weaken the binding strips by perforating 125 them as indicated at 18. Thus each of the binding strips is either broken or weakened after it has performed its function of holding the insole in position on the last bottom until the overwiping or fastening of the shoe 130

upper to the insole. The last may then be readily withdrawn from the shoe in the usual manner by a movement of the last longitudinally of the shoe. The tearable 5 character of the binding strips edgewise, in addition to the weakening or destroying of the binding strips 12 during the lasting and inseam stitching operations on the shoe, causes them to offer little or no resistance 10 to the withdrawal of the last from the shoe. The portions of the binding strips which remain attached to the insole located on the under side of the insole are completely hidden in the completed shoe so that they may 15 remain in the shoe without disadvantage. By securing the insole in position to a last as thus described, the bottom of the last is not damaged as with the tacks heretofore used and the cost incident to the labor and 20 machines required by the use of tacks for securing the insole is eliminated. In addition, a better appearing and more uniform product is made possible since a more accurate pulling-over and lasting condition is obtained than when tacks are used. 25

A further important advantage obtained by the use of the described method is the elimination of the necessity for specially designed devices on the pulling-over and 30 lasting machines to maintain the margin of the insole firmly held down on to the bottom of the last during the operations of the machine.

Having fully described my invention, 35 what I claim as new and desire to secure by Letters Patent of the United States is:

1. That improvement in the art of making shoes which consists in locating an insole on a last bottom, binding the margin 40 of the insole to the last, assembling an upper on the last, and lasting the upper over the margin of the insole while said margin is bound to the last.

2. That improvement in the art of making shoes which consists in locating an insole on a last bottom, binding the margin 45 of the insole to the last, and then sewing an upper to the insole and impairing the effectiveness of the binder as an incident to 50 the sewing operation.

3. That improvement in the art of making shoes which consists in locating an insole on a last bottom and binding the margin of the insole to the last, applying 55 an upper to the last and insole, working the margin of the upper over the last and securing it against the rib of the insole and disrupting the insole binder as an incident to the operations on the shoe after 60 the shoe upper has been folded over the edge of the insole.

4. That improvement in the art of making shoes which consists in locating an insole on a last bottom, and applying a 65 narrow binder of sheet material to the mar-

gin of the insole and bending it down across the edge of the insole and against the side of the last into position to hold the edge of the insole flush with the side of the last, assembling an upper on the last and lasting 70 the upper over the margin of the insole while said margin is bound to the last.

5. That improvement in the art of making shoes which consists in locating on a last bottom an insole, bending down across 75 the edge of the insole a binder affixed to the insole and securing the binder to the side face of the last, assembling an upper on the last, and lasting the upper over the margin of the insole while said margin is 80 bound to the last.

6. That improvement in the art of making shoes which consists in locating on a last bottom an insole, bending down across the edge of the insole a binder affixed to the 85 insole and securing the binder to the side face of the last, repeating the operation of bending down and securing binders at a plurality of points to confine the insole in position with its edge flush with the side 90 face of the last, assembling an upper on the last, and lasting the upper over the margin of the insole while said margin is bound to the last.

7. That improvement in the art of 95 making shoes which consists in locating on a last bottom an insole, bending down across the edge of the insole a binder affixed to the insole and securing the binder to the side face of the last; lasting an upper over 100 the insole margin and the binder; and sewing the upper to the insole and perforating the binder during the sewing operation.

8. That improvement in the art of making shoes which consists in locating on a last 105 bottom an insole having a sewing rib, fastening the insole in place by binders extending outwardly over the sewing rib and feather of the insole and downwardly along and adhering to the side face of the last, applying an upper, and sewing the upper to the rib of the insole and perforating the binders during the sewing operation. 110

9. That improvement in the art of making shoes which consists in locating on a 115 last bottom an insole having a sewing rib, fastening the insole in place by binders extending outwardly over the sewing rib and feather of the insole and downwardly along and adhering to the side face of the last, applying an upper, and lasting the upper over the feather and against the sewing rib and rupturing the binders between the rib and the last by the lasting pressure. 120

10. That improvement in the art of making shoes which consists in locating on a last bottom an insole having a sewing rib, fastening the insole in place by binders extending outwardly over the sewing rib and the feather of the insole and downwardly 125 130

along and adhering to the side face of the last, applying an upper, sewing the upper to the rib of the insole and perforating the binders during the sewing operation, 5 and pulling the last from the shoe and breaking the portion of the binders that adheres to the last from the portion above the line of perforations made during the sewing operation.

10 11. That improvement in the art of making shoes which consists in connecting binders of frangible sheet material to an insole at a plurality of points around its periphery and locating the insole on a last, 15 adhesively connecting the binder ends with the side face of the last to secure the insole in place and hold its margin down to the last, applying a shoe upper and securing it to the insole, and withdrawing the last 20 and tearing the portions of binders which adhere to the last from the portions which are connected to the insole.

12. That improvement in the art of making shoes which consists in securing the 25 margin of an insole to a last by adhesive paper binders, applying and securing an upper, and withdrawing the last from the shoe and tearing the portions of the binders which adhere to the last from the portions 30 which are connected to the insole.

13. That improvement in the art of making shoes which consists in holding the feather of an insole down upon a last bot-

tom by adhesive binding strips that extend down across the edge of the insole and are stuck to the side of the last, applying the upper and shaping it over the feather and securing it, and pulling the last and tearing the binders as the last is withdrawn from the shoe.

40 14. That improvement in the art of making shoes which consists in securing the margin of an insole down upon a last bottom at the sides of the toe and forepart by binders that are connected to the sides of the last and to the insole, assembling an upper and lasting it over the margin of the insole while the insole is so secured, and effecting a relative movement of the last and shoe in the direction to tear the binders 45 edgewise.

15. That improvement in the art of making shoes which consists in holding the margin of an insole down upon a last bottom at the sides by means that are connected to the sides of the last and engage the top face of the insole margin, assembling an upper and lasting it over the margin of the insole and said holding means, and separating the last from the shoe by a movement of the last 50 longitudinally of the shoe until the holding means secured to the last is disconnected from the insole.

In testimony whereof I have signed my name to this specification.

WILLIAM C. STEWART.
